FIG. 2

UNITED STATES PATENT OFFICE.

JOSEPH BERNIER, OF LAC FRONTIERE, QUEBEC, CANADA.

RUT FILLER FOR LOGGING ROADS.

Application filed February 15, 1926. Serial No. 88,457.

This invention relates to new and useful improvements in the method of and apparatus for icing logging roads and the object of the invention is to provide a very simple method of filling up the ruts formed by logging trains on the road beds, said filling up being done economically as regards labour and time required when compared with the system at present in use.

10 Another object is to provide an apparatus of simple construction which will be easy to operate and efficient in action.

As far as I am aware up to the present time, it has been customary to fill up at 15 night or during any such slack period, the ruts cut in the ice road bed by logging trains. This operation is usually accomplished by mounting a water tank on a heavy sled and pulling same over the logging road, 20 allowing water from the tank to flow from said tank into the ruts behind the sled, said water being allowed to freeze and form a good road bed for the passage of a logging train thereover. This entails employment of spe- 25 cial labour and as a rule four or five men are used per team. This forms a very expensive item in logging. In my invention, I provide a much simpler method of repairing such road beds.

30 In my method of accomplishing the above object, I make use of heat to melt the snow or ice surrounding the ruts so that it will flow and level up the bed, and when frozen over will form a first class road for logging purposes. In my preferred form, I make 35 use of a sled having hollow runners which may be heated from any suitable means such as a steam generating plant mounted on a platform secured to the runners. The 40 steam is led from the boiler into the runners and from the runners back into the source of water supply to the boiler, or it may be discharged in such a manner that it will come in contact with the road bed behind the 45 sled to assist in the operation of levelling up same. The sled may be attached to the end of a logging train or it may be used as an independent unit.

In the drawings which illustrate one form 50 of my invention:

Figure 1 is a side elevation of my im- 55 proved icing sled.

Figure 2 is a plan view of the device 60 shown in Figure 1.

Figure 3 is a sectional end view of the 65 runner taken on the line 3—3 Figure 1.

Referring more particularly to the drawings, 11 designates the main body of the runners which are of hollow construction, 60 as shown in detail in Figure 3. Each runner is supplied with an upwardly turned nose piece at each end which closes the ends of the runners forming hollow containers. The noses of the runners may be secured to the main body of the runners by any suitable means (not shown). Extending upwardly from the uppermost surfaces of the runners are the spacers 14 which are recessed as at 15, to receive the brackets 16 which support the platform 17 and also 70 form means for holding the runners in spaced parallel relationship. Mounted on the platform is the boiler 18 which may be heated from any suitable means such as the burner 19. A water tank 20 may also be mounted on the platform and also a coal or fuel holder 21. The boiler and water tank are so mounted on the sled to distribute the load evenly over the bottom of the runners. Water may be fed into the boiler from the 75 tank through the pipe 22 and an injector 23 may be fitted in said pipe in close proximity to the boiler, steam being supplied to the injector through the pipe 24, which is connected to the top of the boiler. The 80 steam generated in the boiler is led through suitable pipe connection into the body of the runners to heat same. In the drawing, I have shown a pipe connection 25^a at the top of the boiler, said pipe connecting with 85 a pair of pipes 25 and 26 running parallel with the runners and approximately midway between them. The pipe 25 is provided with a valve 27 and makes connection with a pair of pipes 28, each connected to one 90 end of the runners. The pipe 26 is also provided with a suitable valve 29 and makes connection with a pair of pipes 30, connected to the other ends of the sleds. The steam 95 which flows into the runners may be discharged therefrom into the water tank through the pipes 31 which may be provided with suitable valves 32, or the steam may be discharged through the pipes 33 and 34, the latter being horizontally disposed 100 and lying parallel and close to the runner with their open ends in close proximity to the noses of the runners, so that the steam

may be discharged directly into the snow or ice forming the road bed to melt same, so that when in liquid form it will level up and then freeze over to form a first class road bed. Valves 35 and 36 may be provided in each of the pipes 34 to control the flow of steam from the runners. Lugs 37 may project upwardly from the nose of the runners so that a spacing bolt 38 may be passed therethrough and held in position by the nuts 39, to hold the runners in parallelism or to form a means for attaching the device to a hauling medium (not shown). Bifurcated lugs 40 may also be provided in the 15 noses at each end thereof for securing the device to a logging train or the like, holes 41 being provided in said lugs for pins, bolts or such like attaining means.

In the drawings I have shown a steam 20 generator for heating the runners, but it will be readily understood that any source of runner heating medium may be used. Other modifications may be made in the general construction of the device, the main object 25 of which is to melt the surrounding snow and fill up ruts in any logging road bed.

In operation the device is attached to any suitable hauling means, such as the end of a logging train. Steam is generated in the 30 boiler and led into the hollow runners preferably at the end nearest the source of hauling. The steam is discharged from the runners so that it will contact with the snow or ice behind the sled or at the end remote from 35 the source of hauling. Valves are provided in the various pipe lines for this purpose. The device shown may be hauled in either direction with equal results and forms a very simple, economical and easily operated device which will be efficient in repairing or 40 filling up ruts cut in the road bed by logging trains.

Having thus described my invention, what I claim is:—

1. An apparatus of the character described comprising a plurality of hollow runners, means for admitting a heating fluid to the interior of said runners, discharge pipes paralleling said runners with the ends of said pipes open and located adjacent the front and rear ends of the runners and means for conducting the heating fluid from the runners to said discharge pipes. 45 50

2. Apparatus of the character described comprising a hollow runner, means for supplying a fluid heating agent to the interior of said runner, a discharge pipe extending longitudinally of the runner at one side thereof, said pipe having both ends open and arranged adjacent the front and rear 55 60 ends of the runner, and a valve controlled connection between said pipe and the interior of the runner whereby the fluid heating agent delivered to the runner may be discharged therefrom through said discharge pipe into contact with the ground at the front and rear ends of the runner. 65

3. Apparatus of the character described comprising a hollow runner, a supply tank containing a fluid heating agent, means for 70 conducting the heating agent from said tank to the interior of said runner, a discharge pipe arranged at one side of the runner, the ends of said pipe being open and located adjacent the front and rear ends of the runner, a return pipe for conducting the heating agent from the runner back to said tank and valve means operable to cause the heating agent contained in the runner to pass outwardly therefrom either through the discharge pipe or the return pipe. 75 80

In witness whereof, I have hereunto set my hand.

JOSEPH BERNIER.
